UNITED STATES PATENT OFFICE.

EDGAR F. SANFORD, OF ALAMEDA, CALIFORNIA.

FIREPLACE-HEATER.

1,322,626.

Specification of Letters Patent. Patented Nov. 25, 1919.

Application filed June 17, 1919. Serial No. 304,758.

To all whom it may concern:

Be it known that I, EDGAR F. SANFORD, a citizen of the United States, residing at Alameda, in the county of Alameda and State 5 of California, have invented certain new and useful Improvements in Fireplace-Heaters, of which the following is a specification.

My invention relates to the class of 10 heaters, adapted to be associated with chimney fireplaces; and it consists in a novel heater of this type intended to utilize as much of the waste heat passing off through the chimney flue, as possible, by causing it 15 to do useful work, both by direct radiation from metal surfaces and by raising the temperature of air drawn into the cavities of said surfaces from the room and delivered to the room again in heated condition.

20 The object of my invention is to provide a simple, easily constructed and readily assembled and installed device for this purpose, which is both economical to manufacture and is effective in operation.

25 Referring to the accompanying drawings—

Figure 1 is a front elevation of a chimney-face with its fireplace, showing the association of my heater therewith.

30 Fig. 2 is a vertical section of the same, taken on the line 2—2 of Fig. 3.

Fig. 3 is a horizontal section on the line 3—3 of Fig. 2.

35 Fig. 4 is a horizontal section on the line 4—4 of Fig. 2.

Fig. 5 is a side view, enlarged, of one of the air-duct elbow castings.

Fig. 6 is an edge view of same.

40 Fig. 7 is a detail, enlarged, of the means for tightening the air-heating drum on the elbow castings at the points where the fit is on a concave, as shown in Fig. 2.

45 1 is the chimney in the face of which is the fireplace 2, with front fender 3 and underlying ash-pit 4, having the front plate 5 with damper 6.

50 The face of the chimney above the fireplace and below the chimney flue 7 is open but is partially covered by a metallic face-plate 8, which closes in the upper part of the opening but exposes its lower portion, as at 9, through which to feed the grate and to see the fire and feel its direct effect.

55 The plate 8 has side legs 10 resting on the fender 3 and said plate is held in place

by a border strip 11 behind which its top and sides are slipped, as seen in Figs. 2 and 3. The said plate 8 is thus a metallic hood heated by the uprising products of combustion and capable of radiating heat 60 into the room; and said plate further serves as a support for the interior air-duct and heating members of the device.

In the legs 10 of the face-plate 8 are made the air-inlet openings 12, and to the inner 65 face of the plate, registering with said openings are riveted at 13, Fig. 1, the inwardly extending metallic side air-duct members 14 which at their inner ends have fitted into them the slip flanges 15 of the air-duct elbow 70 castings 16. These elbow-castings have fitted upon them, by a slip joint, the metallic air heating drum 17, which extends between said castings, and lies within the chimney opening clear of its walls, thus being exposed 75 on all sides to the fire in the fireplace. With the upper central portion of the air-heating drum 17 is connected a communicating air-duct member 18, Figs. 2 and 3, the forward end of which is secured to the 80 face plate 8 behind and registering with an air outlet opening 19 in said plate.

The air from the room enters the heater through the inlet openings 12, passes through the side members 14, the elbow 85 castings 16, the heating drum 17 and member 18 and issues into the room again through outlet opening 19. In its course, it is exposed very fully to the fire and the heated products of combustion, and is thoroughly heated.

80 The device interferes as little as possible with the chimney draft, and leaves the fire itself to be seen and enjoyed in front, through the opening 9. The face-plate 8 95 also serves by radiation to heat the room, and to the same effect the heated members within the chimney opening contribute.

The whole structure can be readily assembled, its members interfitting easily, and 100 by making the slip joints or surfaces of the elbow-castings beveled, as indicated in Figs. 5 and 6, said castings can be fitted to the adjacent members easily and tightly. The drum 17 is held to the elbow castings by the 105 tie bolts 20, and at that place in the slip joint between the two, where the contour is concave, I employ a staple 21, Figs. 7 and 2, one leg of which fits in a socket 22 in the casting and bears with its other leg upon the 110

drum, so that by driving said staple in, the drum is made to conform closely to the casting and make a tight joint.

It will be noted that the elbow castings 16 and the drum 17 which they carry, are bent over at the top horizontally and forwardly in the direction of the front plate 8, as shown at 16' and 17' in Figs. 2 and 3. This has the beneficial effect of more fully heating the contained air by reason of the more direct contact of the uprising products of combustion with said horizontal portion of castings and drum; and it has the further important effect of deflecting the products of combustion toward the front plate 8, thereby better heating said plate and increasing its radiation into the room.

I claim:—

1. A fireplace-heater comprising a face-plate adapted to be fitted to an opening in a chimney above the fire-place, said face-plate having side air-inlet openings and an air-outlet opening thereabove; side air-duct members secured to said face-plate and registering with the air inlet openings; an air heating drum communicating with said side air-duct members, and adapted to lie in the chimney opening clear of the walls thereof; said drum communicating with the air-outlet opening in the face-plate.

2. A fireplace-heater comprising a face-plate adapted to be fitted to an opening in a chimney above the fire-place, said face-plate having side air-inlet openings and an air-outlet opening thereabove; side air-duct members secured to said face-plate and registering with the air-inlet openings; air-duct elbow-castings fitted to the inner ends of the side air-duct members; an air heating drum fitted to said elbow-castings and adapted to lie in the chimney opening clear of the walls thereof; and an air-outlet member fitted to and communicating with the top of the heating drum, said outlet member being secured 45 to the face plate and registering with the air-outlet opening thereof.

3. A fireplace-heater comprising a face-plate fitted to and partially covering an opening in a chimney above the fire-place, said face-plate having legs with air-inlet openings on each side of the exposed portion of the opening, and having also an air-outlet opening above; side air-duct members secured to the legs of the face-plate and reg-

istering with the air-inlet openings thereof; 55 air-duct elbow castings fitted to the inner ends of the side air-duct members; an air-heating drum fitted to said elbow castings and lying in the chimney opening back of the face plate, said side members, elbow 60 castings and drum being clear of the walls of the chimney opening; and an air-outlet member communicating with the upper portion of the drum and with the outlet opening in the face-plate. 65

4. A fireplace-heater comprising a face-plate fitted to and partially covering an opening in a chimney above the fire-place, said face-plate having legs with air-inlet openings on each side of the exposed portion of the opening, and having also an air-outlet opening above; side air-duct members secured to the legs of the face-plate and registering with the air-inlet openings thereof; air-duct elbow castings fitted to the inner ends of the side air-duct members; an air-heating drum fitted to said elbow castings and lying in the chimney opening back of the face plate, said side members, elbow 70 castings and drum being clear of the walls of the chimney opening and said elbow castings and drum having their upper portion bent horizontally forwardly toward the front plate; and an air-outlet member communicating with the upper portion of the 75 drum and with the outlet opening in the face-plate.

5. A fireplace-heater comprising a face-plate adapted to be fitted to an opening in a chimney above the fireplace, said face-plate having side air-inlet openings and an air-outlet opening thereabove; side air-duct members secured to said face-plate and registering with the air-inlet openings; an air heating drum in communication with said 90 side air-duct members, and lying in the chimney opening clear of the walls thereof, said drum having its upper portion bent 95 horizontally forwardly toward the face-plate, and communicating with the air-outlet 100 opening in said plate.

In testimony whereof I have signed my name to this specification in the presence of two subscribing witnesses.

EDGAR F. SANFORD.
